UNITED STATES PATENT OFFICE.

GUSTAVE M. FAUSER, OF ARDSLEY, NEW YORK, ASSIGNOR TO THE PENNSYLVANIA TEXTILE MILLS INC., OF GLENRIDDLE, PENNSYLVANIA, A CORPORATION OF PENNSYLVANIA.

DESIGN FOR A TEXTILE FABRIC.

Application filed December 22, 1922. Serial No. 4,691. Term of patent 3½ years.

To all whom it may concern:

Be it known that I, GUSTAVE M. FAUSER, a citizen of the United States, residing at Ardsley, in the county of Westchester, State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

GUSTAVE M. FAUSER.
